TESTING SYSTEM

Filed Jan. 23, 1923

Inventor:
Harold M. Pruden.
by *E.W. Adams* Atty.

UNITED STATES PATENT OFFICE.

HAROLD M. PRUDEN, OF EAST ORANGE, NEW JERSEY, ASSIGNOR TO WESTERN ELECTRIC COMPANY, INCORPORATED, OF NEW YORK, N. Y., A CORPORATION OF NEW YORK.

TESTING SYSTEM.

Application filed January 23, 1923. Serial No. 614,375.

To all whom it may concern:

Be it known that I, HAROLD M. PRUDEN, a citizen of the United States, residing at East Orange, in the county of Essex and 5 State of New Jersey, have invented certain new and useful Improvements in Testing Systems, of which the following is a full, clear, concise, and exact description.

This invention relates to electrical testing 10 systems and more particularly to systems for testing the adjustment of polarized relays, interrupters and the like.

The object of the present invention is to test the contact adjustment of a circuit 15 changing device such as a polarized relay, while it is in operation.

This is accomplished by translating the pressure between the contacts into a suitable effect, for example, into a varying lamp 20 luminosity indicative of the degree of contact pressure.

The invention will be readily understood from the following detailed description and by reference to the accompanying drawing 25 which shows the testing circuit and visual indicating means employed in detecting the difference in contact pressure exerted by the armature of a vibrating relay on its associated contact and the difference in duration 30 of engagement of the armature with its contacts.

In the drawing a circuit changing device 1, such as a relay arranged for quick connection with and disconnection from the circuit 35 with which it is to be used by means of plugs which are adapted to engage with spring jacks, is shown connected with the testing circuit.

The relay 1 is provided with an armature 40 4 which is caused to vibrate between the stationary contact points 5 and 5^a by means of the operating coils 6. In this connection it is assumed that any well known polarizing means are provided to enable the armature 45 to operate freely upon periodic reversals occurring in the operating current source connected to the terminals 7 and 8. A key 9 is provided for closing the circuit for the operating current through the operating 50 coils 6 and also for placing ground upon the armature 4, the purpose of which will be hereinafter explained.

The actuation of key 9 establishes a circuit which may be traced from the current 55 source (not shown), the lower alternate con-

tact of key 9, the windings of the milliammeter 13, conductor 20, contacts of the plug 2, windings of relay 6, contacts of plug 3, conductor 21, resistance element 15, the upper portion of the potentiometer 12 and back 60 to the original current source. Relay 6 thereupon energizes whereupon its armature 4 alternately engages the contacts 5 and 5^a. When the armature 4 rests on the contact 5^a a circuit exists which may be traced from 65 grounded battery 11, filament of lamp 10^a, contacts of plug 22, contact 5^a, armature 4, contacts of plug 23, to ground over the upper alternate contact of key 9. The lamp 10^a will be illuminated in this circuit. 70

When the armature 4 rests on the contact 5, a circuit may be traced from grounded battery 11, filament of lamp 10, contacts of plug 24, contact 5, armature 4, contacts of plug 23 to ground over the upper alternate 75 contact of key 9. The lamp 10 illuminates in this circuit.

Since the duration of engagement of the armature 4 with the contacts 5 and 5^a depends on the pressure exerted thereon by the 80 armature, it follows that, with a device such as described in which the two circuits are rapidly made and broken, if the contact 5 is so adjusted relative to 5^a that in operating, the armature exerts a greater pressure on 85 contact 5, that is, remains in engagement with it longer than with 5^a, the lamp 10 will glow with a greater brilliancy than lamp 10^a, and conversely. By adjusting the contacts 5 and 5^a until the lamps 10 and 10^a 90 glow with equal brilliancy, a condition is reached where the armature 4 exerts an equal pressure on the contacts 5 and 5^a.

The potentiometer 12, resistances 14 and 15 and the milliammeter 13 are provided so 95 that the operating current may be regulated in such a manner as to test relay 6 under general working conditions.

What is claimed is:

1. In a testing system, in combination 100 with a relay to be tested having an armature adapted to vibrate between two stationary contacts in response to alternating current, a source of alternating current for causing the operation of said armature, a second source 105 of current, a circuit including said armature, said second current source, an indicating lamp and one of said stationary contacts, and another circuit including the same said armature and second current source, another 110

indicating lamp and said other stationary contact.

2. In a testing system, in combination with a polarized alternating current relay to be tested having a reed armature adapted when energized to vibrate between and make contact with two stationary contacts, an indicating lamp for each of said contacts and a source of testing current therefor so connected that one of said stationary contacts, one of said lamps, said current source and said armature are included in one circuit, and the other stationary contact and lamp, and said same current source and armature are included in a second circuit whereby when said armature is vibrated both of said indicating lamps will burn with substantially equal brilliancy when said stationary contacts are properly adjusted with respect to said armature.

3. A contact testing arrangement for polarized alternating current relays of the vibrating reed armature type having two stationary contacts between which said armature is adapted to vibrate and make contact when said relay is energized which comprises a source of testing current, an indicating lamp for each contact, and switching means for connecting in one circuit said current source, one of said lamps, said armature and one of said contacts, and in another circuit said current source, the other lamp, said armature and the other contact, said switching means being also adapted for connecting the operating winding of said relay to a source of operating current.

In witness whereof, I hereunto subscribe my name this 19th day of January A. D., 1923.

HAROLD M. PRUDEN.
